Specification for Design.

Patented June 21, 1921.

Application filed October 30, 1920. Serial No. 420,824. Term of patent 14 years.

To all whom it may concern:

Be it known that I, CLARENCE B. KLOPFENSTINE, citizen of the United States, residing at Des Moines, in the county of Polk and State of Iowa, have invented a new, original, and ornamental Design for a Non-Skid Tread for Tires, of which the following is a specification, reference being had therein to the accompanying drawings.

Figure 1 is a plan view of a section of a tire showing my new design.

Fig. 2 is a cross section view, taken on line 2—2 of Fig. 1.

I claim:

The ornamental design for a non-skid tread for tires, as shown.

In testimony whereof I hereunto affix my signature.

CLARENCE B. KLOPFENSTINE.
